(57) **CLAIM**

We claim the ornamental design for an elevated raceway, as shown and described.

DESCRIPTION

FIG. 1 is a perspective view of an elevated raceway, showing our new design;

FIG. 2 is an enlarged fragmentary view of an upper left-hand portion of the elevated raceway;

FIG. 3 is a front elevational view; and,

FIG. 4 is a top plan view.

The middle portion of the elevated raceway has been shown broken away in FIGS. 1 & 3 to indicate indeterminate height.

The broken line showing of the partition panels is for illustrative purposes only and forms no part of the claimed design. The left and right end views, rear elevational view, and bottom plan view surfaces are not decorative and are not part of the claimed design.
